COMBINATION VENTILATOR AND LADDER FOR TANKS OR THE LIKE

Compere Loveless, Prairie Village, Kans., assignor to Smith & Loveless, Inc., Merriam, Kans., a corporation of Kansas

Application June 6, 1955, Serial No. 513,368

4 Claims. (Cl. 98—33)

This invention relates to equipment for improving the working conditions and safety of workmen who are required to enter tanks and the like, particularly those buried beneath the surface of the ground where it is difficult to provide proper ventilation and evacuation of noxious gases.

It is the most important object of the present invention to provide structure for supplying fresh, dry air to enclosures having no means of normal ventilation and wherein escaping fluids oftentimes present disagreeable, if not dangerous, conditions.

Underground chambers accessible only by way of a manhole or access tube, and especially those employed for the pumping of sewage, are most difficult to ventilate in absence of employment of expensive, complicated and space-consuming equipment. It is necessary not only to bring in clean, dry air, but to remove all disagreeable odors and gases in order to provide satisfactory working conditions when it becomes necessary to maintain service or otherwise attend to the various machinery contained within the chamber.

In accordance with the present invention, therefore, there is provided ventilating means that forms a part of a ladder which may be used in the normal way for entering and leaving the underground chamber, and reference may be had to the accompanying drawings, wherein:

Figure 1 is an elevational view of a tank showing a combination ventilator and ladder made pursuant to the present invention, parts being broken away for clearness.

Fig. 2 is an enlarged plan view showing the cover of the access tube broken away and in section to reveal details of construction.

Fig. 3 is a fragmentary, cross-sectional view taken on line III—III of Fig. 2.

Fig. 4 is a fragmentary, cross-sectional view taken on line IV—IV of Fig. 3.

Fig. 5 is an enlarged, fragmentary, detailed cross-sectional view taken on line V—V of Fig. 2; and

Fig. 6 is a fragmentary, detailed, cross-sectional view taken on line VI—VI of Fig. 1.

The ventilating system contemplated by the instant invention may be used with any underground chamber but has been developed primarily for use as a part of a sewage ejector station wherein an ejector 10, contained within an underground tank 12, received the sewage via inlet 14 and discharged the same through outlet 16. Inasmuch as the tank 12 is normally buried beneath the surface of the ground there is provided an elongated, upright access tube 18 extending upwardly from the tank 12 and in accordance with the present invention, a ladder broadly designated by the numeral 20, is provided and suitably mounted within the tank 12 and the tube 18.

Ladder 20 includes a pair of spaced, upright, hollow side rails 22 and 24 interconnected by a plurality of rungs 26. A combination electrically powered suction blower and dehumidifier 28, secured to the tank 12 from

2

within at the lowermost end of the ladder 20, communicates with the rails 22 and 24 and is provided with a step 30. The unit 28 has an air inlet 32 and is divided into two compartments, 33 and 35 respectively, the latter 5 being a dehumidifying chamber and open at the bottom thereof for drainage of condensate into a sump 34 in the tank 12 as seen in Fig. 1. The sump 34 is drained by use of a pump 36.

A vent cap 38 opening downwardly and mounted on 10 the outer face of the tube 18 at the uppermost end thereof, is provided for each rail 22—24 respectively and communicates therewith through the tube 18 by means of tubular extensions 40 respectively extending from each of rails 22 and 24 to the corresponding cap 15 38. The vent caps 38 serve to mount a cover 42 for the uppermost end of the tube 18 through the medium of pivotally interconnected hinge elements 44 and 45 oppositely attached to cover 42 and the caps 38.

The blower 29 in compartment 33 of unit 28 is controlled by a switch 46 mounted on one of the extensions 20 40. A swingable control arm 48 is actuated by an extension 50 on the lower face of the swingably mounted cover 42.

In operation, when the cover 42 is swung to the position 25 preparatory to entrance into the tank 12, the switch 46 closes to energize the blower 29 in unit 28, thereby drawing air from within the tank 12 via the inlet 32 and forcing the same out through rail 24 and its associated vent cap 38.

30 The incoming air is normally moisture laden and since the same would condense upon contact with the walls of tank 12, such moisture is removed by the dehumidifier 31 in compartment 35 forming a part of the unit 28. This condensate drops into the sump 34 and is ultimately 35 drained from the tank 12 through use of the pump 36.

Air is drawn into tank 12 through rail 22, dehumidifier in compartment 35 and openings 37 formed in the wall of unit 28. When cover 42 is closed the interior of tank 12 and tube 18 is ventilated by blower 28 which is actuated by either a manual switch or an interlock on the 40 motor or starter or a time switch not here shown and that may be disposed within tank 12. When the blower in unit 28 is so actuated, air will be drawn into tank 12 through rail 22 and the dehumidifier in unit 28.

45 Through use of the ladder 20, the operator may enter the tank 12, and by virtue of the automatic nature of the equipment, he is always assured of an evacuation of any fumes or disagreeable odors and gases through the blower and rail 24. After leaving the tank 12 by climbing the ladder 20, the operator closes the cover 42 and the unit 28 is automatically deenergized so far as switch 46 is concerned, but may be actuated without regard to said switch as above set forth.

Having thus described the invention what is claimed 55 as new and desired to be secured by Letters Patent is:

1. In a sewage installation, a tank provided with an access opening and adapted to be at least partially within the ground with said opening located above ground level; 60 an upright ladder within the tank and extending from adjacent said access opening downwardly to adjacent the lowermost portion of the tank, said ladder being provided with at least one elongated, tubular side rail; a rigid, elongated, tubular extension, one end of the extension passing through the side wall of the tank adjacent said 65 opening therein and the opposite end of the extension being connected to and communicating with said one side rail adjacent the uppermost end thereof, said extension serving both as an air current coupling and a means of mechanical support for said one side rail; and blower means mounted within the tank, operably coupled with 70 said one side rail adjacent the lowermost end thereof

and communicating with the interior of said tank for directing artificial currents of air through said one side rail to thereby remove contaminated air from the tank.

2. In a sewage installation, a tank provided with an access opening and adapted to be at least partially within the ground with said opening located above ground level; an upright ladder within the tank and extending from adjacent said access opening downwardly to adjacent the lowermost portion of the tank, said ladder being provided with a pair of spaced, elongated, tubular side rails; a rigid, elongated tubular extension for each side rail respectively, one end of each of said extensions passing through the side wall of the tank adjacent said opening therein and the opposite ends of each of the extensions being connected to and communicating with corresponding side rails adjacent the uppermost ends thereof, said extensions serving both as air current couplings and a means of mechanical support for respective side rails; a dehumidifier mounted within the tank, operably coupled with one of the side rails adjacent the lowermost end thereof and communicating with the interior of the tank; an exhaust blower mounted within the tank, operably coupled with the other of said side rails adjacent the lowermost end thereof and communicating with the interior of the tank; and a cover movably mounted over said opening whereby upon operation of said blower and dehumidifier, contaminated air within the tank is removed therefrom through said other rail and water vapor is removed from the air drawn in through said one rail by said dehumidifier.

3. In a sewage installation, a tank provided with an access opening and adapted to be at least partially within the ground with said opening located above ground level; an upright ladder within the tank and extending from adjacent said access opening downwardly to adjacent the lowermost portion of the tank, said ladder being provided with a pair of spaced, elongated, tubular side rails; a rigid, elongated, tubular extension for each side rail respectively, one end of each of said extensions pass-

5

ing through the side wall of the tank adjacent said opening therein and the opposite ends of each of the extensions being connected to and communicating with corresponding side rails adjacent the uppermost ends thereof, said extensions serving both as air current couplings and a means of mechanical support for respective side rails; an open bottom vent cap for each extension respectively, each of said caps being mounted on the outer portion of said side wall of the tank in overlying, protecting relationship to the outer open end of a corresponding extension; a dehumidifier mounted within the tank, operably coupled with one of the side rails adjacent the lowermost end thereof and communicating with the interior of the tank; an exhaust blower mounted within the tank, operably coupled with the other of said side rails adjacent the lowermost end thereof and communicating with the interior of the tank; and a cover movably mounted over said opening whereby upon operation of said blower and dehumidifier, contaminated air within the tank is removed therefrom through said other rail and water vapor is removed from the air drawn in through said one rail by said dehumidifier.

ing through the side wall of the tank adjacent said opening therein and the opposite ends of each of the extensions being connected to and communicating with corresponding side rails adjacent the uppermost ends thereof, said extensions serving both as air current couplings and a means of mechanical support for respective side rails; an open bottom vent cap for each extension respectively, each of said caps being mounted on the outer portion of said side wall of the tank in overlying, protecting relationship to the outer open end of a corresponding extension; a dehumidifier mounted within the tank, operably coupled with one of the side rails adjacent the lowermost end thereof and communicating with the interior of the tank; an exhaust blower mounted within the tank, operably coupled with the other of said side rails adjacent the lowermost end thereof and communicating with the interior of the tank; and a cover movably mounted over said opening whereby upon operation of said blower and dehumidifier, contaminated air within the tank is removed therefrom through said other rail and water vapor is removed from the air drawn in through said one rail by said dehumidifier.

4. An installation as set forth in claim 1 wherein said blower means is electrically operable, said cover is hingedly mounted on the tank and there is provided switch means on the tank electrically coupled with said blower means, said switch having an actuatable element disposed for actuation upon opening of the cover to thereby control operation of the blower upon opening and closing of the cover.
